CLAIM

The ornamental design for a face mask, as shown and described.

DESCRIPTION

FIG. 1 is a front view of a face mask showing my new design;

FIG. 2 is a rear view thereof;

FIG. 3 is a top view thereof;

FIG. 4 is a bottom view thereof;

FIG. 5 is a right-side view thereof; with the left-side view being a mirror image thereof;

FIG. 6 is a cross-sectional view taken along line 6-6 in FIG. 1; and,

FIG. 7 is an enlarged view of FIG. 6.

The broken lines show portions of the face mask that form no part of the claimed design.

1 Claim, 7 Drawing Sheets
